CLAIM

The ornamental design for a rotatable video cassette holder, as shown and described.

DESCRIPTION

FIG. 1 is a top perspective view of a rotatable video cassette holder showing my new design;

FIG. 2 is a top plan view thereof;

FIG. 3 is a bottom plan view thereof;

FIG. 4 is a front elevational view, the rear being identical thereto;

FIG. 5 is a side elevational view, the side opposite being identical thereto;

FIG. 6 is a top perspective view of a second embodiment, the opposite side being identical thereto; and

FIG. 7 is a top perspective view of a third embodiment the opposite side being identical thereto.
